US00D686093S

(12) **United States Design Patent**
Wright et al.

(10) **Patent No.:** **US D686,093 S**
(45) **Date of Patent:** **** Jul. 16, 2013**

(54) **TIMER**

(76) Inventors: **Jeremy Wright**, London (GB); **Adrian Wright**, London (GB)

(**) Term: **14 Years**

(21) Appl. No.: **29/381,351**

(22) Filed: **Dec. 17, 2010**

(30) **Foreign Application Priority Data**

Jun. 21, 2010 (EM) 001220941-0001

(51) **LOC (9) Cl.** **10-03**

(52) **U.S. Cl.**

USPC **D10/40**

(58) **Field of Classification Search**

USPC D10/40; 368/97-123, 223, 224, 225,
368/233, 77, 239

See application file for complete search history.
